UNITED STATES PATENT OFFICE.

HALDOR A. ANDERSON, OF ORTLEY, SOUTH DAKOTA.

PHOTOGRAPHIC-PRINTING MACHINE.

989,105.

Specification of Letters Patent. Patented Apr. 11, 1911.

Application filed January 29, 1909. Serial No. 474,804.

To all whom it may concern:

Be it known that I, HALDOR A. ANDERSON, a citizen of the United States, residing at Ortley, in the county of Roberts and State of South Dakota, have invented certain new and useful Improvements in Photographic-Printing Machines; and I do hereby declare the following to be a full, clear, and exact description of the invention, such as will enable others skilled in the art to which it appertains to make and use the same.

My invention has for its object to provide an improved photographic printing machine, and to this end, it consists of the novel devices and combinations of devices, hereinafter described and defined in the claims.

The invention is illustrated in the accompanying drawings, wherein like characters indicate like parts throughout the several views.

Referring to the drawings: Figure 1 is a front elevation of the improved machine; Fig. 2 is a plan view of the machine with some parts sectioned on the line $x^2 x^2$ of Fig. 1, and with some parts broken away; Fig. 3 is a vertical section taken approximately on the line $x^3 x^3$ of Fig. 1; Fig. 4 is a view partly in side elevation and partly in vertical section, showing a platen or printing board and an actuating slide, to which it is hinged with the marking device removed; Fig. 5 is a view corresponding to Fig. 4, but showing the platen in a retracted position; Fig. 6 is a detail view, showing the so called curtain actuating slide sectioned on line $x^6 x^6$ of Fig. 2; Figs. 7 and 8 are detail views in section, showing the construction of the hinges and gage pins of a platen; Fig. 9 is a detail view in plan of an adjustable stop for limiting the movement of the platen actuating slide; Fig. 10 is a fragmentary view in side elevation, showing parts of a connection for actuating a so called vignette curtain; Fig. 11 is a detail view partly in plan and partly in section, and some parts being indicated in diagram only, showing on an enlarged scale the so called ribbon receiving and winding device; Fig. 12 is a perspective view showing means for detachably holding one of the feed rollers shown in Figs. 11 and 16; Fig. 13 is a perspective view of a so called ribbon holding device; Fig. 14 is a detail in section taken approximately on the line $x^{14} x^{14}$ of Fig. 13, some

parts being removed; Fig. 15 is a view in elevation, showing a negative plate holder and associated parts; Fig. 16 is a vertical section taken approximately on the line $x^{16} x^{16}$ of Fig. 11, some parts being left in full, some parts being broken away, and some parts being removed; Fig. 17 is a detail view of certain parts found in the vicinity of the line marked $x^{17} x^{17}$ on Fig. 2; Fig. 18 is a rear elevation showing the so called vignette curtain and its guide rollers removed from the machine; Fig. 19 is a detail in front elevation, showing the drum and ratchet wheel of the vignette curtain actuating device; Fig. 20 is a fragmentary view of the parts shown in Fig. 19; Fig. 21 is a perspective view of a so called card holder preferably used in connection with the machine; Fig. 22 is a detail view in side elevation, showing a ribbon marking device which is applied to the platen; and Fig. 23 is a front elevation of the parts shown in Fig. 22.

As introductory to the detail description which will follow, the following remarks are thought to be pertinent: In this improved machine, as preferably constructed, photographic prints may be rapidly made either on a long ribbon or on individual cards or paper sections. When the prints are made on a ribbon, the ribbon is automatically fed intermittently any desired distance, by movements of the so called platen and its actuating slide, so that the photographic print may be repeated over and over again on the same paper or strip. Of course, by changing the negative, any desired number of different prints may also be made on the said ribbon, and the said ribbon may be either of paper or any other properly sensitized or properly prepared paper. When the photographic prints are made on separate cards, these cards will be presented to the negative by a movement of the platen against the negative, and when the platen is retracted, the printed cards will be dropped from the platen and preferably into a suitable receptacle provided therefor.

The preferred construction of the machine is substantially as hereinafter described in detail, and illustrated in the drawings.

The frame work 1 of the machine is preferably of rectangular construction, being provided on top with a face plate 2, and

having at its rear end an upwardly extended back plate 3 which serves as a support for various devices hereinafter described.

So far as the broad idea of my invention is concerned, the negative may be either a film or a glass plate, but as shown, it is of the latter form and is indicated by the character Z. This negative plate Z, when properly positioned, is placed against a glass pane 4, see Figs. 1, 3 and 15. To properly hold and position this negative plate as shown, a pair of arms 5 and 6 are provided at their free ends with pivoted negative clamping bars 7 preferably provided with rubber covered edges 8. The lower arm 6 is pivoted to a thin plate 9, to which the glass pane 4 is detachably secured by strips 10. The said plate 9 is adapted to be detachably secured in a recess 11 of the back plate 3 with the plate 4 and negative Z exposed in a rectangular opening 12 formed in said back plate 3. The upper arm 5 is pivotally connected to a head 13, which as shown, is adjustably secured on a vertical guide rod 14 attached at its ends to the said plate 9, as shown in Fig. 15. The coiled spring 15, yieldingly connects and tends to draw together the arms 5 and 6. A stop screw 16 works through a bearing 17 of the plate 9, and adjustably, but positively, limits the downward movement of the lower arm 6, and hence determines the elevation of the negative in respect to the opening 12. The opening 12, the glass plate 4, and the negative Z, it will be noted, are located above the face plate 2 of the frame 1. The platen 18, at its lower end, is connected by hinges 19 to an actuating slide 20 that is mounted to slide on top of the face plate 2 toward and from the back plate 3, and being as shown, held and guided for such movement by flanged guide strips 21 applied to the opposite edges of the said face plate. A coiled spring 22 tends to turn the platen back or downward on the slide 20, as shown in Fig. 5. When the slide 20 is moved rearward or toward the back plate 3 to an extreme position, the platen 18 is forced against the negative plate Z by means of a lever 23 intermediately pivoted to the slide 20, and having as shown, a roller 24 at its upper end that works on a bearing strip 25 secured to the back of said platen. The lower end of the lever 23 is connected to an anchoring bracket 26, as shown, by means of a jointed rod 27 and a short coiled spring 28, see Figs. 3, 4 and 5. The anchoring bracket 26 is slidably connected to the bottom of the face plate 2, and is subject to an adjusting screw 29 that works through a bearing 30 and is swiveled to said adjustable anchoring bracket 26. The bearing 30 is rigidly secured to the bottom of the face plate 2. The rearward movement of the slide 20 on the face plate 2 is variably limited by a stop 31 adjustably

secured on the face plate 2, and as shown, arranged to work over a relatively fixed graduated scale 32. As will hereinafter appear, the position of the stop 31 determines the amount of feed movement that will be given to the sensitized paper ribbon under return movement of the actuating slide 20. Preferably, the slide 20 is mounted to move on small rollers 33 interposed between recessed portions thereof and the upper surface of the face plate 2.

The anchoring bracket 26 is made adjustable to set the lever 23 and platen 18 to properly hold either thick card or thin paper between the platen and the negative plate, and the spring 28 insures the proper pressure and guards against extreme pressure on the negative plate. The means for holding these cards on the face of the platen, while it is being presented to the negative and for dropping the same from the platen after the print has been made, may take various forms, but in Figs. 4, 5, 7 and 8, it is shown as afforded by so called gage pins 34 mounted for endwise movements in the lower portion of the platen 18. The heads of these gage pins are subject to the free ends of leaf springs 35, the other ends of which springs are secured to the top of the slide 20. The ends of the said spring 35 are so curved, that when the platen is turned downward or retracted from the negative plate, as shown in Fig. 8, said springs will cause the ends of said pins to project and afford supports for the lower edge of the card Y, see Figs. 5 and 8. Preferably, the gage pins 34 are provided with rubber tips and the platen 18 is covered with a cloth facing. When the platen with the applied card Y is turned against the negative plate, the pins 34 are pressed backward as shown in Fig. 7, and the curved end of the springs 35 then press the heads of the said pins at such angle that friction will be sufficient to hold the pins in their retracted positions until the platen is again turned nearly backward to the position shown in Figs. 5 and 8. Hence, under initial movement of the platen away from the negative plate after the print has been made on a card, the said printed card will be free to fall from the platen through a suitable passage in the rear end portion of the face plate 2, onto an inclined chute 36, by which latter, as shown, it will be directed into a drawer 37 mounted in the bottom of the machine case 1. This automatic card holding and dropping mechanism is a very great time saver, and makes it unnecessary to pay any attention whatever to a card after it has been printed, it being simply necessary to return the platen by forward movement of the slide 20 into position for the reception of another card.

In Figs. 1 and 2, the numeral 15 indicates small drawers applied in the front of the

- frame 1, below the face plate 2 and above the drawer 37. These drawers 38 while desirable, are not necessary and form no part of this invention.
- 5 The slide 20 is spring retracted or moved away from the negative plate and preferably, this is accomplished by a quite heavy coiled spring 39 attached at one end to the bottom of the face plate 2, and at its other 10 end to a perforated strap 40, that runs over a pin wheel or hub 41 carried by a small vertical shaft 42, mounted in suitable bearings on the lower portion of the back plate 3. The other end of this strap 40 is attached to one side of a slide 20. For the 15 construction just described, see Figs. 2, 3 and 17. The spring 39 is, of course, more than strong enough to overcome the spring 22.
- 20 For a purpose which will presently appear, the so called pin wheel or hub 41 is formed with ratchet teeth 43 on its upper edge so that it constitutes one member of a clutch device shown in Fig. 16.
- 25 To reinforce or augment the action of the spring 39, a secondary spring device is employed. As preferably constructed, this secondary spring device comprises a bell crank lever 44 which is pivoted to a bearing 45 30 shown as secured to a horizontal partition 1^a of a frame 1. The relatively short lower arm of this bell crank 44 is subject to a leaf spring 46, secured at one end to the said partition 1^a, and having at its free end a 35 seat 47. The relatively long upper end of said bell crank lever 44 is shown as provided with a roller that works between relatively long and short bearings 48 and 49 secured to the bottom of the slide 20, and de- 40 pending freely through an elongated slot in the face plate 2. The operation of this device is as follows: When the parts are in the position shown in Fig. 3, the roller equipped upper end of the bell crank is 45 pressed against the short bearing 49 under the action of the spring 46 on the lower arm of said bell crank; and hence, at this time, the spring 46 co-operates with the spring 39 to insure sufficient force to cause the platen 50 18 to tightly press the card Y against the negative plate. When the slide 20 is drawn outward or retracted approximately to an intermediate position, the end of the lower arm of the bell crank 44 passes into the seat 55 47 of the spring 46, and the roller at the end of the upper arm of said bell crank passes under the short bearing 49, so that the said slide 20 may be freely moved outward to its extreme outermost or retracted 60 position. When the slide 20 is moved forward, the long bearing 48 engages the roller at the upper end of the bell crank and forces the same upward between the said two bearings 48 and 49, and positively forces the 65 lower arm of said bell crank out of the seat

47 of the said spring, so that the said spring again becomes active as above described. Obviously, when the lower arm of said bell crank is in the seat 47 of the spring 46, said bell crank will be temporarily held in 70 a neutral or inoperative position.

Preferably, the cards Y that are to be printed are contained in a box like holder 50 supported by a bracket 51 secured to the back plate 3 above the opening 12 thereof. At 75 its front end, this holder is shown as provided with an inclined end plate 52, and is also shown as provided with an inclined follower plate 53 having a projecting operative bail 54. When the hinged end plate 52 is 80 forced upward, and the follower is forced, forward, a stack of cards contained in the holder may be shifted so that their ends project successively in the same direction, thereby facilitating the picking up of the 85 cards.

The paper ribbon Y¹ upon which the prints may be successively taken, is primarily rolled and preferably contained within a holding drum 55, see Figs. 1, 2, 3 90 and 13, which holder is provided with a hinged side section 56. The drum 55 is rigidly secured to a rectangular supporting frame 57 that is mounted to slide vertically upon the back plate 3. The free edge of the 95 hinged section 56 is shown as provided with projections 56^a adapted to be sprung into notches 58 of upper and lower flanges 59. As shown in Fig. 14, the frame 57 has vertical retaining strips 60 that are adapted to 100 slide upon a thin sheet metal plate 61, which in turn, is directly secured on the back plate 3. As shown, the drum 55 is applied to the left hand end of the vertically adjustable supporting frame 57. To the right hand end 105 of the said supporting frame 57, a ribbon winding or rolling mechanism is applied. This winding mechanism, as shown, comprises as follows: This mechanism is best shown in Figs. 1, 11, 12 and 16. On open 110 ended receiving cylinder or drum 62 is rigidly secured in an upright position to the right hand end of the vertically adjustable bearing frame 57, by means of brackets 63, see Figs. 11 and 16. At its left hand side 115 the receiving drum 62 has a lateral entrance passage 64 for the paper ribbon or strip Y¹. An approximately conical drum bottom 65 is located below the drum 62, and is rotatively mounted in a bearing plate 66 rigidly secured to the frame 57. The spur gear 67 is secured to the rotary bottom 65, and an upwardly extended shaft 68 is secured at its lower end to the said rotary bottom 65, and projects upward axially through the receiving drum 62. A coiled spring blade 69 is secured at the inner edge to the shaft 68. The outer edge of this spring blade 69 is spring pressed against the very smooth inner surface of the receiving drum 62, and 120 125 130

to give the same greater frictional contact with the paper ribbon Y^1 than there is between the said paper ribbon and the smooth inner surface of the drum 62, a thin sheet 5 of rubber cloth or other material 70 is preferably secured to the said spring blade 69, as shown in Fig. 11. The gear 67 meshes with a gear 71 secured on the lower end of a vertically disposed feed roller 72, the shaft of 10 which is mounted in suitable bearings 73 on the bearing frame 57. A small idle ribbon pressing roller 74 is movably mounted in the bearings 73, and is shown as spring pressed against the feed roller 72 by leaf 15 springs 75, secured at one end to the frame 57. The gear 71 meshes with an intermediate gear 76 mounted in suitable bearings 77 secured on the lower portion of the frame 57. The intermediate gear 76 meshes with a 20 driving gear 78, which as shown, is connected by a contracted neck 79 to a sleeve 80, that is telescoped into the lower end of a feed roller 81, and is rigidly secured to said roller. At its upper end, this roller 81 is provided 25 with a headed trunnion 82 journaled in a bearing bracket 83 secured to the upper portion of the frame 57. The roller 81 is therefore, capable of swinging movements at its lower end, but is normally held against such 30 swinging movement by a forked bearing 84 and coöperating spring 85, the former of which embraces the neck 79 of the roller sleeve 80, and the free end of which spring engages an annular shoulder of the gear 78 35 and yieldingly holds the roller 80 against outward swinging movements, see Figs. 12 and 16. A small idle pressure roller 86 coöperates with the roller 81 and is spring pressed toward the same by leaf springs 87 40 applied to the upper and lower portions of the frame 57. The roller 86 is provided at its ends with trunnions that work in slots of the upper and lower bearings 83 and 84 respectively, and the springs 87 directly engage 45 said trunnions, see Figs. 12 and 16. A plunger 88 is mounted for axial movements through the gear 78 and its neck 79 and is connected to rotate with the roller 81, as shown by a cross pin 89 secured to the 50 upper end of said plunger and seated in vertical slots of the roller sleeve 80. A coiled spring 90 yieldingly presses the plunger 88 downward. Rigidly secured to the plunger 88, below the gear 78, is a half clutch 91 that 55 is adapted to engage the half clutch 43 of the pin wheel 41. Also, the plunger 88, below the half clutch 91, is formed with a conical point that is adapted to engage the conical seat in the half clutch 43, and thereby positively hold the roller 81 aligned with the driving shaft 42, see Fig. 16. Preferably, both 60 of the feed rollers 72 and 81 are faced with rubber. If desired, the rollers 74 and 86 may also be rubber faced or covered.

65 When cards are to be printed, the frame

57 and the ribbon actuating devices which are carried thereby, are moved upward on the back plate 3 to the inoperative position shown in Fig. 3, and in this position, the ribbon and its actuating mechanism is preferably contained within a dark box 92 which is provided with a hinged drop bottom 93. In practice, the card box 50 will be offset to one side of the machine so that it does not interfere with vertical movements of the 75 frame 57. When the prints are to be taken on the ribbon, the frame 57 is lowered and the ribbon actuating mechanism is positioned as best shown in Figs. 1 and 2. In this lowered position, the ribbon Y^1 will be 80 fed between the negative plate Z and the platen 18 and by the platen will be pressed against the negative plate, when the slide 20 is moved to its extreme position toward said negative plate. Also at such time, the feed 85 roller 81 is directly connected to the shaft 42 by the engaged clutch members 43 and 41, and the feed roller 72 is indirectly connected thereto through the gears 71, 76 and 78, so that each time the slide 20 is moved 90 outward to contract the platen, a step of movement will be imparted to the paper ribbon Y^1 . The extent of movement thus given to the ribbon will depend on the amount of outward movement given to the slide 20, 95 and through the strap 40 to the pin wheel 41. As already stated, the outward movement of the said slide 20 will be variably limited by the adjustable stop 31. The graduations on the scale 32 indicate the position 100 of the stop 31 for different width photos, such as quarter cabinet, half cabinet, three quarter cabinet and cabinet. Obviously, the winding shaft 68 and its blade 69 are rotated simultaneously with rotation of the feed rollers 72 and 81. The spring blade 69 will press the inner end of the ribbon Y^1 against the inner surface of the drum 62 and cause the same to be wound into a coil. The coiled paper or ribbon will drop into the 105 conical rotary bottom 65, and the latter by its rotary movement, will assist in keeping the paper coiled. When the ribbon has been printed and delivered into the drum 62, it may be readily lifted out of the upper end 110 thereof. The purpose of connecting the roller 81 for swinging movements away from the roller 86 is to permit the paper ribbon to be engaged and started on its travel between the said two rollers. At any time, if desired, the ribbon Y^1 may be cut or severed on a line between the rollers 72 and 81. In Fig. 11, the gears 67, 72, 76 and 78 are shown partly in diagram only, but it will be understood that all of these are complete spur 115 gears.

For marking the backs of the paper strips Y^1 , between prints, so that the proper lines for cutting may be easily determined before the prints are developed, I provide an auto- 120

matic marking device, as shown in Figs. 1, 22 and 23. This marking device comprises an arm 94 which is pivoted to a bearing 95 secured to one edge of the platen 18, and 5 provided at its free end with a pencil holder, as shown in the form of a screw closed split sleeve 96, adapted to hold a short pencil 97. A spring 98 applied to the arm 94 and bearing 95 yieldingly holds said arm 94 against 10 a stop 99 on one end of the platen, and with the point of the pencil projecting beyond the face of the platen, as best shown in Fig. 22, so that when the platen is forced against the ribbon, the point of the pencil will be moved 15 downward on the ribbon and make a mark on the back thereof.

The light controlling curtain 100, see Fig. 3, is mounted on an automatically sprung wound roller 101 of the window shade type, 20 which is supported by the back plate 3 just above the light opening 12. To the lower edge of this curtain 100, the upper ends of a pair of cords 102 are attached. These cords extend downward under guide sheaves 25 103 mounted in openings in the lower portion of the back plate 3, thence upward over similar guide sheaves 104 mounted in the same way in said plate 3, and located very slightly below the face plate 2. From the 30 sheaves 104, the cords 102 extend below the face plate 2 and are attached to depending arms 105, see Figs. 3 and 6 of a supplemental slide 106 mounted to slide on top of the main slide 20 and also held by the flanged guide strips 21. The arms 105 are afforded by the downturned ends of an operating bail or hand piece 107, which is secured to the top of the said supplemental slide 106. A coiled tension spring 108 connects the supplemental 35 slide 106 to the rear portion of the main slide 20, being as shown, attached at its other end to a stop bracket 109 secured to the outer edge of said main slide 20. This stop 109 limits the outward movement of the supplemental slide 106 on the main slide, and the said 40 spring tends to hold said supplemental slide engaged with the said stop.

The hand piece 107 on the supplemental slide 106 affords the primary means for actuating the platen, the light curtain and the ribbon feeding mechanism. Normally the 45 spring 39 holds the platen in its operative position against the negative plate as already described. Normally also the spring 108 will hold the supplemental slide 106 against the stop bracket 109 of the main slide 20, in which position the light controlling curtain 100 will be drawn downward over the light 50 passage 12. The curtain 100 is raised as shown in Fig. 3 by forcing the supplemental slide 106 into its extreme position shown in said Fig. 3, against the tension of the spring 108. Hence, it is necessary to positively hold the supplemental slide 106 in its inner-

most position shown in Fig. 3, long enough 65 to permit the taking of the print, which will, however usually be but a few seconds. When the print is taken, if the supplemental slide be released, the spring 108 will force the same outward against the stop bracket 109, 70 thereby drawing the curtain 100 into its closed position while the platen is still held against the negative plate. To move the platen from the negative plate, the supplemental slide 106, which engaged with the 75 bracket 109, is drawn farther outward, thereby carrying with it the main slide and forcing the platen into its retracted position shown in Fig. 5. The spring 108 should be of greater tension than the spring 39, so that 80 under inward movements of the two slides, it will hold the supplemental slide engaged with the stop bracket 109 until after the spring 39 has forced the platen against the negative plate, thereby preventing the curtain from being moved far enough to open the light passage 12 until after the platen has been forced against the negative plate. 85

Any suitable form of catch or lock device 90 may be employed for securing the main slide 20 and the platen in retracted positions while the negative plates are being changed.

A vignette curtain 110 located outward of the light controlling curtain 100, is connected at its upper end to a spring acting roller 95 111 mounted on the upper portion of the back plate 3. This curtain 111 at its lower edge, has depending strap portions 112 that are secured to a roller 113 mounted in bearings on the lower portion of the back plate 3, 100 and provided at one end with a sheave 114 to which a cord 115 is attached, the other end of said cord being extended forward and attached to a drum 116 mounted on one side of the lower front portion of the case or frame 105 1, see Figs. 3, 10, 18, 19 and 20. The drum 116 is provided with an operating crank 117 and with a ratchet wheel 118, which latter is adapted to be engaged and held by a lock dog 119 pivoted to said case 1. As is evident, the pawl and ratchet device 118-119 serve to hold the curtain 110 with any one of its several light passages alined with the light passage 12, and the back plate 3. The curtain 110 is preferably made of the customary material. The so called light controlling curtain 100 is preferably made of a suitable translucent cloth or material colored yellow or some other color, which will obstruct light rays such as required to print the negative. This curtain from a broad point of view, performs the function of a shutter, but is preferably made translucent so that the operator may see to properly set the negative from the dark room. 115

In practice, I apply a register or counter which is automatically operated by movements of the platen toward and from an 120 125

operative position to indicate the number of prints successively taken from the same negative.

What I claim is:

- 5 1. In a machine of the kind described, the combination with a negative holder, of a slide movable toward and from the said negative holder, a platen carried by said slide and movable thereby against and from 10 the negative holder, and a ribbon-feeding mechanism actuated by said slide and arranged to feed the ribbon between said negative holder and platen.
- 15 2. In a machine of the kind described, the combination with a negative holder, of a slide movable toward and from the said negative holder, a platen carried by said slide and movable thereby against and away from said negative holder, and a ribbon-feeding mechanism having feed rollers and 20 roller driving connections to said slide.
- 25 3. In a machine of the kind described, the combination with a movable platen, of a ribbon feeding mechanism movable from an operative to an inoperative position without being detached, and vice versa, the said ribbon feeding mechanism holding the ribbon in front of the space occupied by said platen, when the latter is in an operative position.
- 30 4. The combination with a platen and a negative holder and means for moving one thereof in respect to the other, of a ribbon-feeding mechanism having feed rollers, and means operated by said movable member 35 for moving said feed rollers intermittently.
- 40 5. In a machine of the kind described, the combination with a negative holder, a platen and a platen-actuating mechanism, of a ribbon-feeding mechanism movable to and from an operative position in respect to said negative holder and platen, and a driving connection between said ribbon-feeding mechanism and said platen-actuating mechanism, including a clutch, the members of which 45 are separable and are engaged when said ribbon-feeding mechanism is in an operative position.
- 50 6. In a machine of the kind described, the combination with a negative holder, a slide and a platen hinged thereto, of means for moving said platen into a vertical position when said slide is moved toward the negative holder, and for turning said platen downward when said slide is retracted, a 55 card-holding device applied to said platen, and means for moving said card-holding device into an operative position when said slide is retracted and said platen turned downward, and for moving said card-holding device into an inoperative position when 60 said platen is moved into an upturned operative position against the negative holder.
- 65 7. In a machine of the kind described, the combination with a negative holder, a slide and a platen hinged thereto, of means for

moving said platen against the negative holder when said slide is moved toward the negative holder, and for turning said platen downward when said slide is retracted.

8. In a machine of the kind described, the combination with a negative holder, of a slide, a spring-retracted platen hinged to said slide, a platen-actuating lever pivoted to said slide, and an anchor connection to said lever, causing the same to force said 75 platen into a vertical position against the negative holder when said slide is moved toward the negative holder, but permitting said platen to be turned downward when said slide is retracted.

9. In a machine of the kind described, the combination with a negative holder, of a slide movable toward and from the negative holder, a platen carried by said slide, a movable curtain working in front of the negative holder, and a connection between the slide and the curtain whereby movements of said slide move said curtain.

10. In a machine of the kind described, the combination with a negative holder, of a slide, a spring for moving said slide toward the negative holder, a platen hinged to said slide, a spring tending to move said platen pivotally downward, but having less tension than the slide-actuating spring, and means for forcing said platen into an upturned operating position when said slide is moved toward the negative holder.

11. In a machine of the kind described, the combination with a negative holder, a slide and a platen carried thereby, of a primary spring device tending to move said slide and platen toward said negative holder and a secondary spring device reinforcing the action of said primary spring device 10 when said platen is moved into an operative position.

12. In a machine of the kind described, the combination with a negative holder and a movable curtain normally located in front thereof, of a primary slide, a platen carried by said primary slide, a secondary slide having a limited movement in respect to said primary slide, and a connection between said secondary slide and said curtain for moving the latter with a properly timed action in respect to the movements of said platen.

13. In a machine of the kind described, the combination with a negative holder and a curtain normally located in front thereof, of a primary slide, a spring tending to move said slide toward said negative holder, a platen carried by said primary slide, a secondary slide having a limited movement in respect to said primary slide, a spring connecting said two slides and tending to move said secondary slide toward the outer extremity of said primary slide, and a connection between said secondary slide and said curtain for moving the same with a 13

properly timed action in respect to the movements of said platen.

14. In a machine of the kind described, the combination with a negative holder, of a slide movable toward and from the same, means for variably limiting the extent of movement of said slide away from said negative holder, a platen carried by said slide, and a ribbon-feeding mechanism for moving the ribbon between said negative holder and platen, including a connection to said slide, whereby the amount of feed movement imparted to the ribbon may be varied by variations in the movement of said slide away from said negative holder.

15. In a machine of the kind described, the combination with a negative holder and a platen movable toward and from the same, of a light-controlling curtain movable in

front of the said negative holder, and a vignette curtain to move inside of said light-controlling curtain.

16. In a machine of the kind described, the combination with a negative holder and a platen and means for moving said platen toward and from said negative holder, of a ribbon-feeding mechanism arranged to feed a ribbon between said negative holder and platen, and an automatic marking device applied to said platen and operative to mark said ribbon when said platen is forced against said negative holder.

In testimony whereof I affix my signature in presence of two witnesses.

HALDOR A. ANDERSON.
